ATTACHMENT PLUG RECEPTACLE

Henry K. Wack, New Bedford, Mass., assignor to
 John I. Paulding, Inc., New Bedford, Mass., a
 corporation of Massachusetts

Application October 11, 1932, Serial No. 637,230

3 Claims. (Cl. 173—330)

This invention relates to an attachment plug receptacle.

One of the important objects of the invention is the provision of a receptacle of the above character having a simplicity of construction which facilitates and expedites the making and assembling of the various parts and thereby effects a material saving in the cost of production.

Another object of the invention is the provision of an insulating body and contacts so formed that the contacts may, in the assembling process, be pushed edgewise into a suitable recess in the insulating body and interlocked to the said body when in final position, without requiring other fastening means.

A further object is the provision of a construction which permits the lead wire terminals to be connected to the contacts on the sides of the receptacle thereby facilitating this operation when the receptacle is being mounted in an outlet box and connected up to a wiring system.

Other objects of the invention will be more specifically set forth and described hereinafter.

In its preferred form, my invention contemplates a receptacle made up of an insulating body recessed from its bottom side to form a contact chamber and contact plates mounted in said chamber from the bottom of said insulating body, the said insulating body and the contact plates having interlocking portions adapted for holding the contact plates locked to the insulating body when in operative position. Preferably, this is accomplished by providing plate contacts adapted to be inserted edgewise into the insulating body in planes parallel with the sides thereof, each contact plate having a portion adapted to lock over a shoulder formed on the side of the insulating body. Midway each side, the receptacle is preferably cut away to expose the contact plate and one or more binding screws may be mounted in said exposed portion so that lead wires may be attached at the side of the receptacle.

This construction has a number of advantages. It conduces to simplicity of construction by reducing the number of parts; eliminates all necessity for providing fastening means such as screws and the like for retaining the contact plates in proper position within the receptacle and it reduces the time and labor necessary for the assembling process.

In the accompanying drawing, showing one form of the invention for the purpose of illustrating the principle thereof, Figure 1 is a top plan view of one form of receptacle constructed

in accordance with my invention; Fig. 2 is a vertical longitudinal sectional view thereof on line 2—2 in Fig. 1; Fig. 3 is a side elevation of the receptacle; Fig. 4 is a bottom plan view; Fig. 5 is a bottom plan view of the receptacle with the yoke and bottom insulating plate removed and showing one contact plate in position; Fig. 6 is a vertical cross-sectional view on line 6—6 in Fig. 1; Fig. 7 is a similar cross-sectional view on line 7—7 in Fig. 1; Fig. 8 is a side elevation of a contact plate and Fig. 9 is an end elevation of the same.

Referring to the drawing, showing the invention embodied in a receptacle of the duplex type, 15 designates a one-piece insulating body of any suitable form but preferably rectangular provided on its upper face with a pair of enlarged projecting bosses 16 adapted to fit openings in the ordinary face plate. In its bottom face, the insulating body is recessed to form a chamber 20 which opens out each side of the insulating body at 22. Mounted in the chamber 20 are two contact plates 25, each comprising preferably an elongated body portion having each end partially separated from the body portion to form a tongue, the free end of which is bent outwardly into offset relation with the body portion to serve as a spring contact blade 26. Each contact plate is mounted edgewise in the chamber 20 adjacent the inner face of one side wall of the insulating body so that the spring contact blades project inwardly toward the longitudinal center of the chamber and in position to be engaged by the blades of a jack plug inserted through jack blade slots 28 which are arranged in pairs in the bosses 16 and open into the chamber 20.

At each end of the chamber is formed integral with the insulating body, an abutment 30, T-shaped in plan (Fig. 5), against which the free ends of the contact blades 26 impinge and which tend to hold those blades in place and to act as guides for the jack plug blades when inserted.

The central portion of each contact plate is exposed by the side opening 22 and in this exposed portion are mounted binding screws 32 for the purpose of attaching lead wires or conductors to the contact plates. Preferably, the plate is stamped out of thin sheet metal in which case it is too thin to permit the holes 34 in which the binding screws are mounted to be threaded. To obviate this difficulty, the central portion of each contact plate is backed up by a rectangular nut 36 having threaded holes to receive the ends of the binding screws which are mounted loosely in the holes 34 in the contact plate. To prevent

inward movement of the contact plate when it is subjected to inward pressure in tightening the binding screws to hold the lead wires, a post 38 is provided in the chamber 20 back of each contact plate, which post may be molded integral with the insulating body. The contact plates are therefore held against lateral movement between the posts and the side walls of the insulating body.

10 In order to lock the contact plates within the insulating body, each of the plates is provided with an inwardly turned portion 40 (Fig. 8) adapted, when the contact plates are pushed into the insulating body, to snap over and lock on a shoulder 42 (Fig. 6) formed on the side of the insulating body above the opening 22. Below this shoulder the side of the insulating body may be bevelled so that when the contact plate is inserted edgewise into the insulating body, the edge of the portion 40 will ride up on the bevelled portion and snap over the shoulder thereby locking the plate in permanent position without requiring any other fastening means.

25 For supporting the insulating body in a suitable receptacle, such as an outlet box, a yoke 44 is fastened to the bottom face of the insulating body longitudinally thereof by a pair of screws 46 mounted loosely in an elongated slot 48 (Fig. 5) in an elliptical post or partition 50 integral 30 with the insulating body. The upper ends of the screws are threaded into a small rectangular plate 52 mounted in a suitable recess formed in the upper face of the insulating body between the two bosses 16, which plate may be provided 35 with a central threaded hole 54 for receiving a screw for fastening a face plate to the insulating body. Between the yoke and the insulating body is interposed a sheet or plate 56 of insulating material which sheet or plate serves merely to 40 close the chamber in the bottom of the insulating body for purposes of insulation since the contact plates are locked within the chamber and require no support. Each end of the yoke is provided with a hole 58 for receiving means for 45 fastening the yoke in an outlet box.

50 It will be observed that a receptacle constructed in accordance with my invention is of very simple construction comprising a minimum number of parts, all of which may be assembled rapidly requiring the manipulation of one screw only. In assembling the receptacle, the contact plates with the nuts and binding screws are inserted edgewise in the bottom of the receptacle and pushed inwardly until the portion 40 on each 55 contact plate rides over its respective shoulder 42 and snaps into place thereby locking each contact plate in operative position. The insulating sheet 56 and yoke are then adjusted in position and fastened by the manipulation of the screws 60 46 which completes the assembling.

65 In addition to the convenience in assembling, it will be observed that my invention permits the lead wires to be attached to the receptacle at the sides thereof, a position which facilitates the installation of the receptacle in an outlet box and its connection to the wires of the circuit. The contact plate is of extremely simple construction and can be stamped out of ribbon metal in one operation and the locking of those members in 70 the insulating body does not require any screws or other fastening means but is accomplished by merely pushing the contacts into operative position.

It is to be understood that my invention is not to be limited to the construction hereinbefore shown and described since it may be embodied in various other forms all within the scope of the following claims.

What I claim is:

1. In a device of the character described, an insulating body recessed in its bottom face to form a chamber, said chamber opening out each side of said body and said body having an outer shoulder on each side adjacent said side opening, a pair of jack blade slots in the upper face of said body at each end thereof and opening into said chamber, an abutment formed in said chamber at each end thereof, said abutment having oppositely faced portions serving as guides for jack blades inserted in said slots and a pair of contact plates mounted edgewise in said chamber, each of said plates having a flange overlapping one of said shoulders for locking said contact plate within 10 said chamber, and each of said plates being provided with an offset spring contact blade at each end, each of said blades being normally in engagement with an oppositely faced portion of said abutments to hold said contact plate against 15 lateral movement in said chamber.

2. In a device of the character described, an insulating body recessed in its bottom face to form a chamber, said chamber opening out each side of said body and said body having an outer shoulder on each side adjacent said side opening, a pair of jack blade slots in the upper face of said body at each end thereof and opening into said chamber, an abutment formed in said chamber at each end thereof, said abutment having oppositely faced portions serving as guides for jack blades inserted in said slots, and a pair of contact plates mounted edgewise in said chamber, each of said plates engaging the inner face of a side wall of said body and having a flange 30 overlapping one of said shoulders for locking said contact plate within said chamber, and each of said plates being provided with an offset spring contact blade at each end, each of said blades being normally in engagement with an oppositely faced portion of said abutments to hold said contact plate against 35 lateral movement in said chamber.

3. In a device of the character described, an insulating body recessed in its bottom face to 50 form a chamber, said chamber opening out each side of said body and said body having an outer shoulder on each side adjacent said side opening, a post formed in said chamber adjacent each side opening, a pair of jack blade slots in the 55 upper face of said body at each end thereof and opening into said chamber, an abutment formed in said chamber at each end thereof, said abutment having oppositely faced portions serving as guides for jack blades inserted in said slots, and a pair of elongated contact plates mounted each edgewise in said chamber between a side wall and one of said posts, each of said plates having a central flange overlapping one of said shoulders for locking said contact plate within said chamber, and each of said plates being provided with an offset spring contact blade at each end, each of said blades being normally in engagement with an oppositely faced portion of said abutments to hold said contact plate against lateral movement 65 in said chamber.

HENRY K. WACK.
